UNITED STATES PATENT OFFICE.

MARTIN D. GOURLAY, OF NORTH ATTLEBORO, MASSACHUSETTS.

DESIGN FOR A BEDSPREAD.

Application filed February 23, 1928. Serial No. 25,545. Term of patent 7 years.

To all whom it may concern:

Be it known that I, MARTIN D. GOURLAY, a citizen of the United States of America, residing at North Attleboro, in the county of Bristol and State of Massachusetts, have invented a certain new, original, and ornamental Design for Bedspreads, of which the following is a specification, reference being had to the accompanying drawing, forming part thereof.

The drawing is a plan view of the bedspread constituting my design.

I claim:—

The ornamental design for a bedspread, substantially as shown.

In testimony whereof I affix my signature.

MARTIN D. GOURLAY.
